[57] CLAIM

The ornamental design for a baby walker, as shown and described.

DESCRIPTION

FIG. 1 is a perspective view of a baby walker showing our new design;

FIG. 2 is a left side elevation view thereof, the right side elevation view being a mirror image of that shown;

FIG. 3 is a top plan view thereof;

FIG. 4 is a bottom plan view thereof;

FIG. 5 is a front elevation view thereof; and

FIG. 6 is a rear elevation view thereof.

FIG. 1

FIG. 2

FIG. 3

FIG. 4

FIG. 6
